CLINICAL-CHIRURGICAL-ROBE

América Fundora de Lasarte, Habana, Cuba

Application March 6, 1937, Serial No. 129,466

7 Claims. (Cl. 2—114)

This invention relates to garments and more particularly to garments and gowns for surgical or clinical purposes where different anatomical portions of a person's body may be exposed for observation or operation purposes and at the same time enable the garment to preserve the neat appearance and design of ordinary wearing apparel. A gown of this type may also be employed as a maternity garment where it is desired to adjust the size of the garment from time to time and also expose the breast portions of the body in a convenient, comfortable and accessible manner without unduly exposing the person.

15 An important object of the present invention is to provide a surgical or maternity garment of novel design and arrangement which shall permit ready access to all principal parts of the body, or any one particular portion of the 20 body while concealing the other parts from view.

Another object of the invention is to provide a garment of the character designated having front and rear portions which may be opened at various places to expose the front or rear portions of the body without removing the garment from the person.

Another object of the invention is to provide a garment of the character designated which shall be adjustable and form fitting in style so 30 as to maintain the same in a neat and pleasing appearance as an ordinary house garment.

A further object of the invention is to provide a garment of the character designated having a novel form of cape which shall cooperate with the waist and skirt portions of the gown to facilitate the use of the garment for a greater variety of uses and add to the appearance of the same.

These and other objects of the invention will 40 be more manifest from the following specification and drawings and more particularly set forth in the claims.

Referring to the drawings:

Figure 1 is a front view of the garment,

45 Figure 2 is a rear view of the garment shown in Fig. 1,

Figure 3 is a front pattern view,

Figure 4 is a similar view with the front portion opened and;

50 Figure 5 is a pattern view of the cape.

Referring to Figures 1 and 2 of the drawings, there is shown a garment constituted and arranged in accordance with the present invention and comprises a blouse or waist portion 10 and a skirt 11. The skirt is of the wrap type

overlapping at the back. The waist 10 and skirt 11 are united at the waist line by a waist band or belt 12 stitched thereto and provided with tapes 13 and 14 which overlap and tie in the front as indicated by the numeral 15.

As shown in Figure 3, one side of the band 12 is provided with an opening 16 for receiving the opposite tape 13 and thus enable the skirt band portions 12 to overlap and thus be adjustable to any sized person and also hold the garment in a neat and form-fitting appearance at the waist.

The blouse 10 is of the backless type and is formed by providing tapering sides 17 and 18 upwardly from the band 12 to a relatively narrow neck band portion 19 secured by tapes 20 and 21 in the usual manner. The blouse and skirt are cut away to provide a large front central opening indicated by the numeral 22 as shown in Figure 4. This opening is closed or covered by 20 a pleated flap 23 which runs from the bottom of the skirt to a position above the breast portion of the blouse as shown in Figure 3. The flap is detachably secured to the upper portion of the blouse by suitable fasteners such as buttons 24, 25 and 26 and holes 24', 25' and 26' respectively, as shown in Figure 4. This flap is also secured to the waist band 12 in a similar manner by buttons 27 and 28 and holes 27' and 28'. The bottom of the flap is permanently secured 30 to the skirt below the central opening as shown by the concealed stitching indicated by the numeral 29. This flap 23 may also be in the form of one large pleat and stitched at the inside of the spaced seams indicated by dotted lines 30—30. 35

The skirt portion is also provided with small pleated portions 31 and 32 which are gathered at the waist band 12 and sewed thereto. These pleats may be conveniently let out when it is desired to enlarge the skirt.

Another important feature of the improved garment is the arrangement of the blouse to provide a brassière for holding the breasts in proper form as well as concealing the same from view when the flap 23 is open for inspection of 45 the abdomen of the person. The brassière is made by gathered portions 33 and 34 forming the upper edge of the opening 22 in the blouse. These gathered portions are adapted to receive a draw string 35 so that the size may be adjusted as desired. The brassière as well as the opening in garment front are completely covered by the flap 23 when the same is secured by the top button fasteners 24, 25 and 26.

Another important feature of a garment con- 55

structed and arranged in accordance with the present invention is the provision of a cape 36 for covering the arms and shoulders. This cape also includes a rectangular flap member 37 secured thereto for overlying and covering the opening formed by the backless portion of the blouse. This cover portion is sewed to the inside of the cape 36 adjacent the neck portion as indicated by stitching 38 so that it is free to cover the back 10 and be tucked under and be secured by the waist band 12. The cape is further removably secured in place by the provision of button holes 40 and 41 on the marginal front edges. These holes are adapted to be engaged by buttons 24, 25 and 26 15 at the front portion of the blouse so that the cape shall be adjusted to size and convenience of the person.

Having thus described a clinical or maternity garment constructed and arranged in accordance 20 with my invention, the many features and advantages are as follows: The garment as shown in Figures 1 and 2 entirely covers all parts of the body and presents a neat and dressy appearance. When an examination of any part of the anatomy 25 is desired, that part of the body may be exposed without unduly exposing the surrounding parts. For example, if an inspection of either or both arms is desired, the cape may be loosened by front bottoms 24 and 26. If an inspection of the 30 back is desired, the cape with its flap 37 is removed. Then again if the abdomen portion of the body is to be exposed, the flap 23 is lowered to the waist by loosening only top buttons 24, 25 and 26. When such an examination is made, the 35 brassière portions 33 and 34 conceal the breasts. If the physician desires to examine the breasts, the brassière portion is loosened. In a similar manner it will be obvious that the garment may be opened at any principal part of the anatomy without unduly exposing the surrounding parts.

40 Another important feature of the novel garment arrangement is that if the patient is too ill to be moved, the entire garment may be removed or changed with a minimum amount of disturbance to the patient by loosening the waist band 45 ties 13—14 and the neck band ties 20—21.

Another important feature is that the blouse 10 and skirt 11 may be made of a single piece of material, and the provision of the several pleats in the skirt and a gathered neck band 19, the 50 garment may be quickly and comfortably adjusted to any ordinary sized person.

Having thus described a garment embodying my invention it is obvious that various changes may be made therein without departing from the 55 invention as defined in the claims.

Having thus fully described my said invention, what I claim as new and desire to secure by Letters Patent is:

1. A garment of the character described comprising a backless and sleeveless waist member 5 and a skirt member united at the waist line of the garment, a neck member for holding the upper portion of the waist in form fitting position, an opening formed in the front portion of the garment and extending from below the waist line 10 of the skirt to the breast region of the waist member, a detachable flap for closing the opening, and means for detachably securing the flap at the waist line and the breast region whereby different portions of the flap may be opened to 15 conveniently expose a desired anatomical portion of a person without unduly exposing the adjacent portions.

2. A garment of the character described in claim 1 in which the waist member is provided 20 with means at the top portion of the opening for enclosing the breasts of a person when the flap is opened.

3. A garment of the character described in claim 1 in which the waist member is provided 25 with an adjustable brassière member at the top portion of the opening and underlying the flap, and means for opening the brassière as well as fitting the same to the breast region of a person.

4. A garment of the character described in 30 claim 1 including a cape member having a flap attached to the inside thereof and adapted to cover the backless portion of the waist.

5. A garment of the character described in claim 1 including a cape member having a flap 35 attached to the rear inside neck region thereof and adapted to extend downwardly past the waist line to cover the backless portion of the waist.

6. A garment of the character described in claim 1 including a cape member having a flap 40 attached at the neck region thereof and adapted to cover the backless portion of the waist, means for securing the flap at the waist line of the skirt, and means for adjustably attaching the front edges of the cape to the waist.

7. A garment of the character described in claim 1 in which the waist and skirt members are integrally united, the skirt being of the wrap type and provided with waist band tapes, and an opening provided at the waist line of the skirt and at one side of the opening for receiving a tape of the opposite skirt side, whereby the skirt may overlap at the back and be secured at the 50 waist line in front of the garment and overlie the flap.

AMÉRICA FUNDORA DE LASARTE.
